UNITED STATES PATENT OFFICE.

EDWARD P. BAKER, OF DARIEN, CONNECTICUT.

DEVICE FOR FACILITATING THE REMOVAL OF VALVES.

1,168,145.

Specification of Letters Patent. Patented Jan. 11, 1916.

Application filed February 23, 1915. Serial No. 10,081.

To all whom it may concern:

Be it known that I, EDWARD P. BAKER, a citizen of the United States, residing at Darien, in the county of Fairfield and State 5 of Connecticut, have invented certain new and useful Improvements in Devices for Facilitating the Removal of Valves; and I do hereby declare the following to be a full, clear, and exact description of the invention, such as will enable others skilled 10 in the art to which it appertains to make and use the same.

This invention has for its object to provide a novel and efficient device for facilitating the removal of engine valves.

Another object is the provision of a device for removing spring closed engine valves capable of a wide range of adjustment and including means for reliably locking 20 the parts in adjusted position.

With these and other objects in view, the invention consists in the novel construction, arrangement and formation of parts as will be hereinafter specifically described, claimed 25 and illustrated in the accompanying drawing, in which:

Figure 1 represents a side elevation of the device applied to use. Fig. 2 represents an enlarged side elevation of the device removed and partly in section. Fig. 3 represents a transverse sectional view on the line 3—3 of Fig. 2, and Fig. 4 represents a transverse sectional view on the line 4—4 of Fig. 2.

Referring to the drawing, wherein similar reference numerals designate corresponding parts throughout the several views, the numeral 5 indicates a cylindrical bar having external screw threads and an angularly directed end 6 formed with an inwardly directed longitudinal recess or slot 7. A relatively adjustable arm 8 is formed in one end with an opening 9 having a plain inner surface slidably receiving the externally screw-threaded bar 5. A pair of nuts 10 are threaded upon the bar 5 and are adapted to be turned up against the opposite sides of the arm 8 to reliably secure the lat-

ter in adjusted position upon the bar 5. The opposite end of the arm 8 is formed 50 with an internally screw threaded opening 11 receiving a screw 12 having a head or handle 13 at its upper end. A head 14 is removably threaded upon the inner end of the screw 12, and is preferably of polygonal 55 formation as illustrated in Fig. 4.

In use, the valve stem or rod 15 is engaged within the slot 7 in such relation that the angular end 6 of the bar is disposed between the spring 16 and the pin 17 positioned through the valve stem or rod 15, carrying the valve 18. The arm 8 and screw 12 are subsequently adjusted so as to engage the head 14 with the upper surface of the valve 18, and the screw 12 is rotated so as 65 to draw the angular end 6 of the bar upwardly toward the arm 8, thus compressing the spring and removing the lower end of the latter from the pin 17, which latter may be quickly and conveniently removed and the 70 valve 18 and stem 15 subsequently removed.

It will be understood that the arm 8 is rotatable upon the externally screw threaded bar 5 and may be adjusted angularly with 75 relation to the angular end 6 of the bar. The nuts 10 engage against the opposite sides of the arm 8 reliably securing the latter in adjusted position upon the bar 5. When it is desired to remove a relatively small valve, the polygonal head 14 is preferably removed from the screw 12, so as to permit the end of the latter to engage directly upon the upper surface of the valve.

What I claim is:

1. A device for facilitating the removal 85 of valves, comprising a bar having an angularly directed end formed with an inwardly directed longitudinal slot, an arm adjustably mounted on said bar, means for securing said arm in adjusted position, a screw 90 fitted in the end of said arm opposite said bar, and a polygonal head having an internally screw threaded recess receiving the inner end of said screw.

2. A device for facilitating the removal 95 of valves comprising a screwthreaded bar,

an angularly directed end on said bar, an arm having an opening adjacent one end slidably and rotatably receiving said bar, a pair of nuts fitted on said bar and en-
5 gaging the opposite side faces of said arm for securing the latter in adjusted position on said bar, a screw fitted in the opposite end of said arm, and a polygonal head hav-

ing an internally screwthreaded recess receiving the inner end of said screw.

In testimony whereof I affix my signature in presence of two witnesses.

EDWARD P. BAKER.
